 werk, Siemensstadt near Berlin, Germany

Application October 27, 1937, Serial No. 171,203
 In Germany November 6, 1936

12 Claims. (Cl. 179—26)

The present invention relates to a circuit arrangement for semi-automatic telephone systems such as are used for example in local and toll systems in which automatic exchanges with central battery feeding are associated with small local battery rural exchanges. In such systems calls from subscribers of the automatic exchanges are set up completely automatically, while calls from subscribers of the local battery rural exchanges are set up with the aid of an operator.

In the case of calls of the last type various switching operations such as ringing, setting of switches, and release are transmitted back over the established connecting path. Since the connecting path passes over a plurality of connecting lines coupled by repeaters the switching operations are transmitted for the most part by the same signals, i. e., short alternating current impulses over the connecting lines and short direct current impulses within the exchanges. The switching operations are differentiated in the receiving connecting devices in that different receiving relays are provided for receiving the impulses in dependence upon the stage reached in the establishment of the call. Now it may happen that in a connecting device a switching measure taken on the part of the operator, e. g., ringing, coincides with a switching measure in the opposite direction on the part of the calling subscriber. In accordance with the stage reached in the establishment of the call the signal transmitted by the subscriber tends to lead the impulses from the operator to a receiving relay which is not that provided for the switching operation occurring at that time. The impulses from the operator thus promote a false switching operation, such as the false setting of switches.

The invention aims at avoiding this difficulty in that two simultaneous signals arriving at a connecting device from opposite directions influence separate receiving relays while auxiliary relays are provided which are influenced partly from one of the receiving relays in such a manner that the switching over of the receiving circuit of the counter-direction by one of the receiving relays on a third receiving relay only takes place after the termination of the signal proceeding from the counter-direction.

The attached drawing represents one embodiment of the invention.

Fig. 1 is a diagrammatic representation of a local and toll system with automatic exchanges B, C and D and a local battery rural exchange A.

Fig. 2 shows the relevant details of the repeater 55 Ue1 in the exchange B. In addition there is

shown the secondary switch MW with its wipers *am*, *bm*, and *cm* and the testing relay P1 and also the impulse contact 37h2 of the repeating relay in the repeater Ue2.

Referring now to Fig. 1, the general operation of the system will be explained. Calls which are set up from subscribers of the automatic exchange B, C and D proceed automatically while calls which are set up from subscribers of the rural exchange A are set up with the aid of an operator whose position VPL is disposed in the exchange D. If a subscriber of the exchange A, for example subscriber Tn1, desires to set up a call to subscriber Tn4 of the automatic exchange B the following switching operations occur:

Subscriber Tn1 operates a magneto with which every subscriber's station of the exchange A is provided and thereby starts up the call finder AS which sets itself on the calling line. When this has occurred the connecting switch AW is set automatically on the call finder AS. The repeater Ue1 in exchange B is seized over the connecting line VL1 by the connecting switch AW. This automatically starts up a secondary switch MW which becomes set on a free alternating current repeater Ue2. The alternating current repeater Ue3 in the exchange C is seized by the repeater Ue2 over the connecting line VL4. This repeater has access to a first group selector GWc. The first group selector GWc is raised to the first level by an impulse automatically transmitted from the repeater Ue1. It rotates freely searching for a free alternating current repeater Ue8. From the repeater Ue8 an incoming alternating current repeater Ue11 is reached in the exchange D over the connecting line VL5. The repeater Ue11 has access to a second group selector GWd. The group selector GWd is then raised to the second level by two impulses which are transmitted automatically from the repeater Ue1. It hunts over this level and seizes a free exchange position VPL. A call indicating lamp is thereupon lit up at the operator's position. The operator plugs into the seized jack. She thereby transmits a signal to the repeater Ue11 for example in the form of potential of one of the speaking leads. This signal is translated into an alternating current impulse which is sent back over the connecting line VL5 to the repeater Ue8. Here it is converted back into a direct current signal which is transmitted to the repeater Ue3. At this repeater the direct current signal is converted into an alternating impulse which is sent back over the connecting line VL4 to the repeater Ue2, in the exchange B. The alternating current

55

impulse is again converted into a direct current potential namely a transitory application of potential to the *b*-lead which influences a relay connected to the *b*-lead in the repeater *Ue1*. The 5 result of this influencing is that by the transitory application of a direct current signal to the *a*-lead in the repeater *Ue1* and impulse is transmitted forward and passes over the connecting line *VL4* to the repeater *Ue3* as an alternating current impulse. This alternating current impulse 10 causes switching in the repeater *Ue3* which enables the operator at the position *VPL* to transmit selecting impulses back over the line and thereby to complete the connection.

15 If after initiating the call by operating a magneto at his station the calling subscriber in the local battery exchange *A* has remained at his station and has taken up his receiver a second impulse is transmitted from the repeater *Ue1* 20 which passing over the connecting line to the operator's position *VPL* operates there a supervisory lamp as a signal that the calling subscriber is at his station. The operator can thereupon commence to dial and set the selectors giving access 25 to subscriber *Tn4*, namely the first group selector *GWb* and the final selector *LWb*.

If, however, after operating his magneto the calling subscriber has not yet taken up his receiver he must first be called by the operator. 30 For this purpose the operator switches over a so-called ringing switch, this transmits a permanent direct current signal to the repeater *Ue1* which is translated into an alternating current impulse train at this latter repeater which is 35 maintained until the ringing switch is switched back again. This impulse train passes back over the line *VL5* to the repeater *Ue3*. Here it is 40 translated into a direct current impulse train and after being converted in the repeater *Ue3* into an alternating current impulse train passes as a 45 direct current impulse train to the repeater *Ue1*. Now it may happen that at the moment at which the ringing current impulse train reaches the repeater *Ue1* from the operator, the calling subscriber 50 replies and accordingly a direct current signal is also transmitted forwardly to the repeater *Ue1* over the connecting path which has 55 been set up. The reply signal from the calling subscriber now effects a disconnection of the ringing current receiving relay from the line in the normal way and in its place connects up a receiving relay which is to receive the selecting impulses transmitted by the operator. Naturally 60 the reply signal also tends to bring about the same switching operation if it is received simultaneously with ringing current impulses from the operator. Thus it may happen that 65 since ringing current impulses and selecting impulses cannot be differentiated the incoming ringing current impulses operate upon the receiving relay provided for setting the switches on the called subscriber's station. In this way a false setting of these switches would be caused. The arrangement according to the present invention 70 avoids this.

The individual switching operations in so far as they are necessary for enabling the invention to be understood will now be described with reference to Fig. 2. As soon as the call finder *AS* 75 and the connecting switch *AW* have become set on the calling subscriber's line after the latter (subscriber *Tn1* for example) has initiated a call, potential is connected temporarily to the *a*-lead in the connecting switch *AW* and thereby 80 relay *A1* is energized over contact *20c1*, winding

II of relay *A1* and earth. Relay *A1* locks up in the following circuit: earth, winding I of relay *A1*, contact *29a1*, the winding of relay *C1*, battery and earth. Relay *C1* also energizes in this circuit. The *a*-lead is switched through by relay *C1* at its contact *30c1*. Relay *A1* causes the secondary switch *MW* to be started up.

The secondary switch is set in known manner with which the present invention is not concerned. When the secondary switch has found 10 a free line the testing relay *P1* energizes over the test wiper *cm* and the seizing relay of the repeater *Ue2*. This brings the secondary switch to rest and guards the seized line. The seizure is extended to the repeater *Ue3* and to the group selector *GWc* from the repeater *Ue2*. Relay *P1* 15 switches through the speaking leads to the repeater *Ue2* at contacts *2p1* and *3p1*. In addition relay *P1* starts up an auxiliary switch of which only wiper *di* is shown. The impulses are transmitted automatically over this wiper and set the switches *GWc* in the exchange *C* and *GWd* in the exchange *D*. As is indicated in the figure these impulses are transmitted over wiper *di* in 20 the repeater *Ue1* by the connection of earth potential to the *a*-lead on particular contacts of the switch.

After the switch *GWd* has been set on the operator's position *VPL* the operator receives a call 25 indicating signal. When in response to the call indicating signal the operator plugs into the seized jack, potential is transitorily applied to the *c*-lead. This direct current impulse passes over the connecting line *VL5* to the exchange *C* as an alternating current impulse. It is here 30 translated into a direct current impulse and re-converted into an alternating current impulse which passes over the line *VL4* to the repeater *Ue2* and from there passes over the *b*-lead to the repeater *Ue1* as a direct current impulse. In 35 the repeater *Ue2* a repeating relay *H2* is energized temporarily by this impulse. This relay closes the following circuit for relay *E1* in the repeater *Ue1*: earth, battery, contact *37h2*, wiper *bm*, contact *4p1*, and *5x1*, winding of relay *E1* 40 and earth. Relay *E1* energizes and energizes relay *B1*: earth, contacts *21p1* and *22e1*, winding of relay *B1*, battery and earth. Relay *B1* locks up over contact *23b1* independently of relay *E1* 45 which releases after a short time. After relay *E1* has released the following circuit is completed for relay *N1*: earth, contacts *13c1*, *12e1*, *19b1* and *8f1*, winding of relay *N1*, contacts *10m1* and *11n1*, resistance *Wi*, battery and earth. Relay *N1* 50 energizes and connects earth to the *a*-lead over its contact *7n1* and the closed contact *1p1*. This earth potential operates as an impulse on the repeater *Ue2* and is transmitted over the line *VL4* to the repeater *Ue3* and switches over its 55 repeater so that impulses transmitted from the operator's position *VPL* can be received. The connection of earth potential to the *a*-lead over contact *7n1* is terminated by relay *M1* energizing in series with relay *N1* after the opening of contact *11n1*. Relay *M1* short-circuits relay *N1* 60 over contact *9m1* and relay *N1* releases and terminates the impulse transmitted to the repeater *Ue2*. Relay *M1* locks up over its contact *9m1* in the circuit: earth, contacts *13c1*, *12e1*, and *9m1*, winding of relay *M1*, resistance *Wi*, battery 65 and earth.

After the release of relay *N1* relay *Dr* is connected to the *a*-lead which leads to the connecting switch *AW* over contacts *38m1*, *39n1* and *30c1*. In this switch a relay which is not shown is con- 75

nected to earth and this relay causes the speaking leads to be switched through to the calling subscriber. Relay Dr energizes in the above-mentioned circuit and closes contact 40dr.

5 If the waiting subscriber has remained at his station, relay Y energizes in the repeater Ue1 over the loop closed when the receiver is taken up: potential on the a-lead, the calling subscriber's loop, the b-lead, contact 32f1, the winding of relay Y and earth. Relay Y energizes and short circuits relay M1 over earth, contacts 14y and 42z1. Relay M1 releases. Relay Z1 now energizes in the following circuit: earth, contacts 14y and 17m1, winding of relay Z1, battery and earth. Relay Z1 locks up independently of contact 17m1 over its contact 15z1. After relay M1 has released relay N1 energizes again over earth, contacts 13c1, 12e1, 19b1, 8f1, the winding of relay N1, 10m1 and 11n1, resistance Wi, battery and earth. Relay N1 transmits another short impulse over contact 1n1 to the repeater Ue2 over the a-lead. This impulse is extended to the operator's position VPL after corresponding conversation. At the operator's position a supervisory lamp is operated indicating that the calling subscriber has replied. At the same time the transmission of ringing current impulses from the operator's position is prevented. The impulse is terminated in the repeater Ue1 through relay M1 energizing in series with relay N1 after the opening of contact 11n1. Relay M1 short-circuits relay N1 whereupon the latter releases while the former holds up.

After relays Z1 and M1 have energized the following circuit is set up for relay X1: earth, contacts 28c1, 26m1, 25z1, the winding of relay X1, battery and earth. Relay X1 locks up over its contact 24x1 independently of relay Z1. Relay X1 by opening its contact 5x1 disconnects relay E1 from the a-lead and in its place connects the impulse receiving relay J1 over contact 6x1.

When the operator transmits impulses from the exchange position VPL for setting the switch on the desired subscriber's line relay H2 is again energized impulsively in the repeater Ue2, this relay completing the following circuit for relay J1: earth, battery, contact 37h2, wiper bm, contacts 4p1 and 6x1, the winding of relay J1 and earth. The first impulse energizes a relay Q1 which is not shown and which seizes the group selector GWb over contact 36q1 and lead c. The impulses are transmitted over earth, contact 35j1 and the a-lead to the impulse receiving relay in the group selector GWb.

If the calling subscriber after having transmitted the call initiating impulse by operating his magneto has not remained at his station, relay Y in the repeater Ue1 does not energize. The exchange operator must accordingly ring the subscriber. She therefore throws over her ringing key and thus transmits impulses to the repeater Ue1 so long as the ringing switch is operated. These impulses again impulsively energize relay H2 in the repeater Ue2. Relay E1 energizes again in the repeater Ue1 over contact 37h2. Relay E1 then closes the following circuit for relay F1: earth, contacts 16c1, 18e1 and 40dr, the winding of relay F1, battery and earth. Relay F1 energizes and being slow to release holds up throughout the ringing impulses. Relay M1 also holds up in the same way in spite of contact 12e1 temporarily breaking the locking circuit for relay M1 at each impulse. A constant potential is applied to the b-lead to the connec-

tion switch AW over a choke-coil Sn and contact 31f1 and causes a source of ringing current to be connected to the calling line at this switch.

At the end of the ringing impulse relay E1 finally releases. Relay F1 releases in consequence. When now the calling subscriber replies potential is applied to the b-lead from the connecting switch AW in response to which relay Y in the repeater Ue1 energizes. Relay Y short-circuits relay M1 at contact 14y and relay M1 releases. Relay N1 can now energize and applies a temporary earth to the a-lead over its contact 7n1. An impulse is thus transmitted to the operator's position VPL indicating to the operator that the calling subscriber has replied. At the same time the transmission of ringing current from the operator is prevented by this impulse. The impulse is terminated by the energizing of relay M1. During the release of relay M1 relay Dr holds up over contact 48y1 and the a-lead to the connecting switch.

After relay M1 has released relay Z1 energizes again over earth, contacts 14y and 17m1, the winding of relay Z1, battery and earth. Relay X1 is then operated over contacts 25z1 and 26m1. At contact 5x1 relay X1 disconnects the ringing receiving relay E1 from the b-lead and over contact 6x1 connects up the impulse receiving relay J1 in its place. The operator can now transmit impulses to relay J1 to set the group selector GWb and the final selector LWb on the connection of the wanted subscriber Tn4.

It may happen that the calling subscriber replies at the same moment at which the exchange operator transmits back ringing impulses. Relay E1 becomes energized by the ringing impulses and relay Y by the reply impulse from the calling subscriber simultaneously. Now irrespective of the time at which the two signals reach the repeater relay E1 must be prevented from being prematurely disconnected by relay Y and relay J1 from being connected to the b-lead in its place because the ringing impulses, which just as the selecting impulses, are transmitted by the application of potential to the b-lead over contact 31h2 in the repeater Ue2, must be prevented from influencing the impulse receiving relay J1. Otherwise this would result in a false setting of the switches.

The undesirable event of the simultaneous reception of both signals occur if the first ringing impulse from the operator's position VPL arrives at the moment at which the earth impulse produced by the reply signal of the calling subscriber is transmitted over contact 7n1 and the b-lead. When this occurs relay Y has been energized by the calling subscriber's relay signal and relay M1 releases thereby connecting up relays Z1 and N1 simultaneously. Since relay M1, which is slow to energize, has not yet energized relay X1 cannot yet energize over contact 26m1 in this case and no switching over of the b-lead from relay E1 to relay J1 can take place. When now relay E1 is energized by the first ringing impulse the circuit for relay N1 and for relay M1 disposed in series with it is immediately broken by the opening of contact 12e1. Relay N1 releases again and relay M1 is not energized again. Relay F1 becomes energized by relay E1 over contact 18e1. Relay F1 breaks a further point in the circuit for relays N1 and M1 at contact 8f1. Relay F1 being slow to release holds up during the ringing impulse. Relay Y is disconnected from the b-lead by contact 32f1. Relay Y releases again and relay Z1 holds up.

over earth, contacts 13c1, 51z1, 17m1 and 15z1, the winding of relay Z1, battery and earth. During the release of relays N1 and Y1 relay Dr is held energized in the following circuit: earth, contacts 43p1, 44f1, winding II of relay Dr, contact 47dr, battery and earth.

At the end of the ringing impulses relay E1 releases finally and relay F1 deenergizes in consequence. Since the calling subscriber is still at his station relay Y energizes again over contact 32f1. After relays E1 and F1 have released relay N1 also energizes again. Over contact 7n1 relay N1 transmits a short reply impulse over the a-lead to the repeater Ue2 whence it is extended to the operator's position. After the opening of contact 11n1 relay M1 energizes again in series with relay N1. Relay X1 now energizes again over earth, contacts 28c1, 26m1 and 25z1, the winding of relay X1, battery and earth. Relay X1 energizes and locks up independently of relay Z1. Relay X1 disconnects relay E1 from the b-lead and connects relay J1 in place of it.

The operator now sends back impulses which cause the switches to be set in the wanted subscriber's line through the intermediary of relay J1.

In the case in which, when the two signals are received simultaneously, the earth impulse transmitted by the reply signal of the calling subscriber has already been transmitted over contact 7n1 and the a-lead, i. e., if relay M1 has already energized in series with relay N1, ringing impulses can no longer be transmitted back by the operator because the subscriber's reply impulse has already been received at the operator's position and the transmission of the ringing current is prevented so that the switching over of the ringing key by the operator is rendered inoperative.

Release takes place either automatically after the expiry of given time, or in response to the calling subscriber replacing his receiver. Relay Y in the repeater thereupon release and relay A1 is short-circuited and deenergizes whereupon relay C1 also releases and in consequence all the other relays.

I claim:

1. Signalling apparatus for use in a telephone system comprising, a line, a relay normally connected to said line and responsive to signalling in one direction thereover, a relay normally disconnected from said line, and means responsive to signalling in the opposite direction over said line for causing said first relay to be disconnected from said line and said second relay to be connected to said line to respond to signalling in said one direction thereover, said first relay effective when connected to said line and actuated thereover to render said last means ineffective.

2. In a telephone system, a subscriber's station and a line therefor, an operator's position, a trunk line, means for completing a connection between the subscriber's line and the operator's position over the trunk line, means for extending a branch connection from said last connection, a control device for said last means, another device connected to the trunk and actuated thereover by the operator for causing the subscriber to be signalled, a third device connected to the trunk and actuated thereover by the subscriber for causing the second device to be disconnected from the trunk and the first device to be connected to the trunk, said first device then controllable by the operator to direct the extension of said branch connection, and

means controlled jointly by the second and third device and effective, responsive to actuation of the second device by the operator and concurrent actuation of the third device by the subscriber, to cause the actuation of the third device to be rendered effective to cause the second device to be disconnected from the trunk and the first device to be connected thereto only upon termination of the actuation of the second device.

3. In a telephone system, a subscriber's station and a line therefor, an operator's position, a trunk line, means for completing a connection between the subscriber's line and the operator's position over the trunk line, means for extending a branch connection from said last connection, a control device for said last means, another device connected to the trunk and actuated thereover by the operator for causing the subscriber to be signalled, a third device connected to the trunk and actuated thereover by the subscriber for signalling the operator's position to prevent actuation of the second device by the operator and for causing the second device to be disconnected from the trunk and the first device to be connected to the trunk substantially simultaneously with the termination of said signalling, said first device then controllable by the operator to direct the extension of said branch connection, and means controlled jointly by the second and third devices and effective responsive to the concurrent actuation thereof for causing said signalling to be interrupted and the actuation of the third device to be rendered effective only upon termination of the actuation of the second device to cause the operator's position to be signalled and to cause the second device to be disconnected from the trunk and the first device to be connected thereto substantially simultaneously with the termination of the signalling.

4. In a signal receiving device for use in a telephone system, a plurality of lines terminating in the device, signal receiving means normally connected to one of said lines, signal receiving means normally disconnected from said one line, and means connected to another of said lines and operable thereover both to cause an impulse of current to be transmitted over said one line thereby to promote the blocking of signalling to said device over said one line and also to cause said first means to be disconnected from said one line and said second means to be connected to said one line substantially simultaneously with the cessation of the transmission of said impulse, said first means effective, if actuated over said one line before the transmission thereover of said impulse, to render the operation of said last means ineffective for so long as the actuation persists.

5. In a signal receiving device for use in a telephone system, a plurality of lines terminating in the device, signal receiving means normally connected to one of said lines, signal receiving means normally disconnected from said one line, and means connected to another of said lines and operable thereover both to cause an impulse of current to be transmitted over said one line thereby to promote the blocking of signalling to said device over said one line and also to cause said first means to be disconnected from said one line and said second means to be connected to said one line substantially simultaneously with the cessation of the transmission of said impulse, said first means effective, if actuated over said one line during the transmission thereover of said impulse, to cause the impulse to be

- interrupted and said last means to be rendered ineffective for so long as the actuation persists, said last means then effective upon subsequent deactuation of said first means to cause the 5 pulse of current to be transmitted and to cause said first means to be disconnected from said one line and said second means connected thereto.
6. Signalling apparatus for use in a telephone 10 system comprising, a line, a relay connected to the line and responsive only to signalling current transmitted thereover in one direction, a second relay connected to said line and responsive only to signalling current transmitted thereover in the 15 opposite direction, a third relay, a fourth relay for disconnecting the second relay from the line and for connecting the third relay to said line to respond to signalling current transmitted thereover in said opposite direction, and a circuit controlled jointly by the first and second 20 relays for actuating the fourth relay only when signalling current in but said one direction is transmitted over the line.
7. Signalling apparatus for use in a telephone 25 system comprising, a line, a relay connected to the line and responsive only to signalling current transmitted thereover in one direction, a second relay connected to said line and responsive only to signalling current transmitted thereover in the opposite direction, a third relay, a fourth relay for disconnecting the second relay from the line and for connecting the third relay to said line to respond to signalling current transmitted thereover in said opposite direction, and a circuit controlled jointly by the first and second 30 relays for actuating the fourth relay a predetermined interval of time after the receipt of signalling current transmitted in said one direction unless signalling current transmitted to the opposite direction is received during that time 35 interval, said circuit effective if signalling current transmitted in the opposite direction is received during that time interval to cause the fourth relay to be actuated a predetermined time interval after the cessation of the transmission of current in the opposite direction.
8. In combination, three relays, a circuit controlled by two of the relays for energizing the third relay when said two relays are energized together, a circuit controlled by one of the two relays for initially energizing the second of the two relays when the first relay is deenergized, a circuit for energizing the first relay, an incomplete shunt circuit about the first relay prepared 40 by the second relay when deenergized, and means for completing the shunt circuit to deenergize the first relay and thereby cause the second relay to be energized over the second circuit, the second relay thereupon effective to complete a locking circuit for itself and to open the shunt circuit, said first relay then effective to reenergize over said third circuit to cooperate with the sec- 45
- ond relay in causing the third relay to be energized over the first circuit.
9. Signalling apparatus for use in telephone or like systems, comprising, a line, a relay, means responsive to signalling over said line in one direction for conditioning said relay to receive signals subsequently transmitted over the line in the opposite direction, and means responsive to signalling over said line in said opposite direction prior to the conditioning of said relay for 5 rendering said first means ineffective for so long as said signalling in said opposite direction persists.
10. Signalling apparatus for use in telephone or like systems, comprising, two signalling circuits, a relay, means responsive to signalling over one of said circuits for conditioning said relay to receive signals subsequently transmitted over the other one of said circuits, and means responsive to signalling over said other circuit prior to said conditioning of said relay for rendering said first means ineffective for so long as said signalling over said other circuit persists.
11. Signalling apparatus for use in telephone or like systems, comprising, a line, a signal receiving device, means for both transmitting a transitory signal over the line in one direction to promote blocking of signalling over the line in the opposite direction and, substantially simultaneously with the termination of the transmission of said transitory signal, conditioning said device to respond to signalling over the line in said opposite direction, and means responsive to signalling over the line in said opposite direction before the transmission of said transitory signal thereover for rendering said first means ineffective for so long as said signalling in said opposite direction persists.
12. Signalling apparatus for use in telephone or like systems, comprising, a line, a signal receiving device, means for both transmitting a transitory signal over the line in one direction to promote blocking of signalling over the line in the opposite direction and, substantially simultaneously with the termination of the transmission of said transitory signal, conditioning said device to respond to signalling over the line in said opposite direction, and means responsive to signalling over the line in said opposite direction during the transmission of said transitory signal thereover for interrupting said transitory signal and rendering said first means ineffective for so long as said signalling in said opposite direction persists, said first means then effective upon termination of said signalling in said opposite direction to transmit said transitory signal and, upon termination of the transmission of said transitory signal, to condition said device to respond to subsequent signalling over the line in said opposite direction.

EDUARD WOCHINGER. 60
